FOREIGN PATENT DOCUMENTS

EP	0373724 B1	3/1993
EP	0556967 A2	8/1993

Primary Examiner — John Windmuller*Assistant Examiner* — Steven Czyz(74) *Attorney, Agent, or Firm* — Patzik, Frank & Samotny Ltd.(57) **CLAIM**

The ornamental design for a floor mat retaining cleat, as shown and described.

DESCRIPTION

FIG. 1 is a front perspective view of the floor mat retaining cleat of the present invention;

FIG. 2 is a front elevation plan view of the floor mat retaining cleat of the present invention, the rear elevation view being a mirror image thereof;

FIG. 3 is a left side elevation view of the floor mat retaining cleat of the present invention, the right side elevation view being a mirror image thereof; and,

FIG. 4 is a top plan view of the floor mat retaining cleat of the present invention.

The bottom of the floor mat retaining cleat is plain and unadorned, and does not form part of the design.

The broken lines depict portions of the article that form no part of the claimed design.

1 Claim, 4 Drawing Sheets(56)
